UNITED STATES PATENT OFFICE.

BRADFORD C. GIBBS, OF PITTSBURGH, AND HARRY P. REIBER, OF WILKINSBURG, PENNSYLVANIA.

BOILER-GAGE GUARD.

1,264,785.

Specification of Letters Patent. Patented Apr. 30, 1918.

Application filed April 7, 1917. Serial No. 160,399.

To all whom it may concern:

Be it known that we, BRADFORD C. GIBBS and HARRY P. REIBER, citizens of the United States, and residents of Pittsburgh and 5 Wilkinsburg, respectively, in the county of Allegheny and State of Pennsylvania, have invented a new and useful Improvement in Boiler-Gage Guards; and they do hereby declare the following to be a full, clear, and 10 exact description thereof.

Our invention relates to boiler gage guards or shields, and more particularly to that class of guards used for preventing particles of broken gage tubes flying and 15 injuring workmen or others, and has for one of its objects the provision of such a device that will provide a clear vision of the gage at all times.

A further object is to overcome the difficulties heretofore encountered in such devices by their cumbersome and complex methods of attachment to the gages and also to provide a device that may be opened 20 to permit the insertion of a new gage glass 25 without dismantling.

Another object is to provide a ventilating back to prevent steaming and sweating, and also a back greatly facilitating the reading of the gage.

Our gage guard and shield is for use to 30 protect the workmen from injury and is a "safety-first" device. The department of labor and industry of the different States requires that all boiler gages be protected, 35 and our device thoroughly protects those employed in and around such gages, and at the same time facilitates reading of the gage, for the reason that the apertured back-plate when viewed through the tubular 40 column of water in the gage causes the apertures to appear as a scale, and to cause the water level to be more clearly defined.

In order that our invention may be fully understood, we have described one embodiment thereof in the following specification and illustrated it in the accompanying drawings. It will be understood, however, that our invention may be embodied in other forms, and that changes may be made in design, 45 sign, without departing from the scope thereof, as defined in the appended claims.

In the drawings:

Figure 1 is a perspective view of our improved gage;

Fig. 2 is a similar view with the front 55 casing open;

Fig. 3 is a view on the line 3—3, Fig. 1;

Fig. 4 is a top plan view of the back plate;

Fig. 5 is a front plan view of the back 60 plate;

Fig. 6 is a top plan view of the front casing;

Fig. 7 is a front plan view of the same;

Fig. 8 is a perspective view of one of the 65 U-shaped supporting members; and

Fig. 9 is a modified form of a similar member.

Referring more particularly to the drawings the letter A designates the device as a 70 whole, which comprises a back plate 10 having a rectangular aperture 11 inclosed by a perforated plate 12. Tubular hinge members 13—13 and 14—14 are formed at the upper and lower corners of the plate 10 re- 75 spectively.

The back plate 10 is provided with supporting lugs 15—15 at top and bottom adapted to engage between the nipples 16 and the body of the valves 17. U-shaped 80 clamping bands 18 are passed around the valves and have their free ends passing through apertures in the back plate 10 and are secured by nuts 19.

The front 20 and sides 21 and 22 are composed preferably of heavy plate glass, but 85 it will be readily understood that isinglass, or other such material may be employed. The members 20, 21 and 22 are supported and held together by U-shaped channel top 90 and base supporting members 23 and 23^a, forming a closure casing B, the inner walls 24, 24^a and 24^b of which are composed of lugs cut from the base of the member and bent upwardly.

The members 23 and 23^a are apertured at 95 25 for the reception of the rods 25^a having threaded terminals 26. The rods are adapted to draw the members 23 and 24 into firm engagement with the front 20 and sides 21 100 and 22 and hold said members in position by nuts 27.

Apertured lugs 28, 28 and 29, 29 are formed on the members 23 and 23^a respectively and are adapted to coöperate with the 105 tubular hinge members 13—13, and 14—14 respectively.

Locking rods 30 and 30' are adapted to

be passed through the members 13—28 and 14—29 on each side of the device to secure the front 20 and sides 21 and 22 to the back plate 10.

5 If a gage tube becomes broken it is not necessary to remove our device to replace the gage, but only to remove one of the rods 30 or 30' and open the closure B, the other rod serving with the members 13—28 and 10 14—29 to form a hinge bearing.

The advantages of our construction will be readily apparent; first the water level is at all times visible; second the device need not be removed to replace the gage; third 15 it facilitates reading; fourth that it may be readily attached or detached; and fifth that it is an absolutely safety-first device.

Having described our invention, what we claim is:

- 20 1. A boiler gage guard comprising a back plate, a casing secured to said back plate, said casing comprising transparent front and side members, U shaped channel members engaging the ends of said front and 25 side members, means for securing said channel members together, and U-shaped clamping members passing through and adjustable relative to said back plate for holding said casing in position on a gage.
- 30 2. A boiler gage guard comprising a back plate, and a casing secured thereto, said casing comprising U-shaped channeled base and

top members, transparent front and side members supported in said U-shaped members, and tie rods extending through said U- 35 shaped members and adapted to hold said casing together.

3. In combination with a water gage of a boiler, a guard, comprising a perforated back plate, and a casing secured thereto, said 40 casing comprising U-shaped channeled base and top members, transparent front and side members supported in said U-shaped members, and tie rods extending through said U- 45 shaped members and adapted to bind said casing together.

4. A boiler gage guard comprising a back plate and a casing, said casing comprising channeled base and top members, transparent front and side members supported in 50 said base and top members, and tie rods extending through said base and top members, said casing being detachably secured to said back plate, and clamping members engaged in said back plate for securing said guard in 55 position.

In testimony whereof, we the said BRADFORD C. GIBBS and HARRY P. REIBER, have hereunto set our hands.

BRADFORD C. GIBBS.
HARRY P. REIBER.
